COMBINATION EDGE TURNING AND
WELDING DIE

Eiwood C. Bolles and Joseph Wind, Jr., Pacific Grove, Calif., assignors to Chris-Craft Industries, Inc., a corporation of Delaware

Filed June 15, 1960, Ser. No. 36,499
9 Claims. (Cl. 156—479)

The invention relates to a combination edge turning and vulcanizing die and refers more particularly to apparatus for folding cover material of trim panels over the edge of the foundation board of the trim panel and for holding the cover material in assembly with the foundation board while the cover material is secured to the foundation board electronically.

It is an object of the invention to provide an improved combination edge turning and vulcanizing die.

Another object is to provide a combination edge turning and vulcanizing die for use with electronic sealing apparatus.

Another object is to provide a combination edge turning and vulcanizing die for use in securing the cover material of a trim panel to the foundation board thereof which die includes means for embossing the surface of the trim panel.

More specifically it is an object to provide a combination edge turning and vulcanizing die comprising a die base including means for resiliently supporting cover material for a trim panel, a die lid for positioning a trim panel foundation board on the cover material and pressing the foundation board and cover material against the resilient support therefor, said die including means for folding the cover material against the edge of the foundation board when the foundation board and cover material are pressed against the resilient support therefor, and glide block and sliding plate means for folding the cover material against the surface of the foundation board remote from the die base while the foundation board and cover material are pressed against the resilient support therefor and for holding the cover material and foundation board in assembly while they are secured together.

Another object is to provide a combination edge turning and vulcanizing die as set forth above wherein said die lid and the sliding plates of the guide block and sliding plate means are resiliently supported for movement toward or away from the die base.

Another object is to provide a combination edge turning and vulcanizing die as set forth above wherein said die lid and the sliding plates of the guide block and the sliding plate means are insulated from the die base to facilitate electronic sealing of the cover material to the foundation board of a trim panel held in said die.

Another object is to provide a combination edge turning and vulcanizing die as set forth above wherein said die base comprises a substantially flat base plate, a bonding rule secured to said base plate, said bonding rule extending perpendicularly outwardly from said base plate and being in configuration of an edge seal between the cover material and foundation board of a trim panel which it is desired to produce therewith, a turning rule for folding the cover material into engagement with the edge of the foundation board, said turning rule being positioned adjacent the bonding rule and outwardly with respect to a trim panel positioned on the bonding rule, said turning rule extending outwardly from the die base a distance greater than the bonding rule, and resilient supporting material positioned on the base plate within the area defined by the bonding rule.

Another object is to provide a combination edge turning and vulcanizing die as set forth above wherein the

2

die lid comprises a substantially flat plate hingedly secured to the die base at one side thereof on a resilient mounting for pivotal movement and for movement perpendicular with respect to the die base, said die lid including means for locating a foundation board relative to the die base.

Another object is to provide a combination edge turning and vulcanizing die as set forth above wherein the guide block and sliding plate means comprises guide blocks secured to said die base adjacent said turning rule and sliding plates mounted on said guide blocks for movement parallel to the base plate which sliding plates on movement toward the bonding rule are operable to turn the edge of cover material positioned between the die base and die lid into engagement with the surface of the foundation board remote from the die base.

Another object is to provide a combination edge turning and vulcanizing die as set forth above which is simple in structure, economical to manufacture and efficient in use.

Other objects and features of the invention will become apparent as the description proceeds, especially when taken in conjunction with the accompanying drawings, illustrating a preferred embodiment of the invention, wherein:

FIGURE 1 is a top view of a combination edge turning and vulcanizing die constructed in accordance with the invention.

FIGURE 2 is a section view of the combination edge turning and vulcanizing die illustrated in FIGURE 1 taken on the line 2—2 in FIGURE 1.

FIGURE 3 is a diagrammatic representation of the combination edge turning and vulcanizing die illustrated in FIGURE 1 in combination with a press and means for producing an alternating electrical signal between the press platens.

FIGURES 4 and 5, and FIGURE 6 are section views of the combination edge turning and vulcanizing die of the invention taken on the lines 4—4 and 6—6 respectively in FIGURE 1 and showing the die lid and sliding plates in progressive edge folding positions.

With particular reference to the figures, one embodiment of the invention will now be disclosed.

As shown in FIGURE 1 the edge turning and vulcanizing die 10 of the invention comprises a die base 12, a die lid 14 and a plurality of guide block and sliding plate means 16. Said die lid 14 and guide block and sliding plate means 16 are secured to the die base 12 as shown.

In the embodiment of the invention shown cover material 18 for a trim panel of an automobile or the like and bonding material 20 are positioned on the die base 12. A foundation board 22 for the trim panel is positioned on the open die lid 14. The die lid is then closed to position the foundation board on the cover material and fold the cover material into engagement with the edge 24 of the foundation board. The cover material is next folded into engagement with the side 26 of the foundation board remote from die base 12 by the guide block and sliding plate means 16. Subsequently the die 10 is placed in a press and the cover material is secured to the foundation board electronically.

More specifically the die base 12 as shown best in FIGURES 1 and 2 comprises a flat base plate 28 which is rectangular in outline and has secured thereto the angle shaped bonding rule 30. Bonding rule 30 is formed in the configuration of the seal it is desired to produce between the cover material 18 and foundation board 22 of a trim panel as shown best in FIGURE 1. The connection between the base plate 28 and the bonding rule 30 is an electrical connection.

The die base 16 further includes the turning rule 32 secured to the bonding rule 30 by convenient means, such

as bolts 34. The turning rule 32 as will be seen from the figures is spaced from the bonding rule 30 by spacer 36 and extends perpendicularly to the base plate 28 a distance greater than the bonding rule 30. Turning rule 32 extends adjacent the bonding rule 30 on three sides of the die base 16 shown in FIGURE 1.

A resilient member 38 is positioned on the base plate 28 over the area defined by the bonding rule 30. The resilient member as shown in FIGURE 4 when not compressed extends perpendicularly outwardly from the base 10 plate 28 of the die base 16 the same distance as the turning rule 32.

In the embodiment of the invention illustrated the base plate 28 is magnesium while the bonding rule 30 is aluminum. The turning rule 32 and the spacer 34 are of 15 neoprene plastic or other insulating material. Sponge rubber may be used for the resilient member 38.

Die lid 14 comprises a substantially flat rectangular magnesium plate 49 which has a covering 42 of neoprene on the side adjacent the die base with the die lid 14 in 20 the closed position as shown in FIGURE 2.

The die lid 14 as shown in FIGURE 2 is mounted on the base plate 28 of the die base 16 by means of piano hinge 44 and the micarta block 45 and springs 47 in conjunction with guide means 48 and bolts 49. Die lid 14 is thus resiliently supported for movement perpendicularly to the die base 16 as will be understood by those in the art.

A pair of L-shaped brackets 50 are secured to and a recess 51 is provided in die lid 14. The L-shaped brackets and recess in cooperation with a mating boss on foundation board 22 serve to locate the foundation board 22 with respect to the die base 12 and cover and bonding material 18 and 20 positioned thereon.

Each guide block and sliding plate means 16 comprises micarta guide blocks 52 secured to the base plate 28 in position adjacent the turning rule 32 as shown in FIGURES 1 and 2. The guide blocks 52 as best shown in FIGURE 6 have an elongated recess 54 in the upper surface 56 thereof into which a sponge rubber pad 58, a micarta plate 60 and a T-shaped aluminum slide 62 are positioned in order. Aluminum guide plates 64 are secured to the surface 56 of guide blocks 52 and extend along and over the longitudinal edges of the recess 54 as shown, to retain the slides 62 in the recess 54. Magnesium sliding plates 66 having a rubber covering 68 on the surface thereof closest the slides 62 are secured to the slides 62 by convenient means such as screws 70 as illustrated.

The sponge rubber pad 58 is provided to permit movement of the sliding plates 66 perpendicular to the die base 12 to maintain the surface 72 of the sliding plates and the surface 74 of the die lid in the same plane on placing of the die 10 between the platens 76 and 78 of the press 80.

The sliding plates 66 may be moved horizontally into a position over the turning and bonding rules 32 and 30 as shown in FIGURE 6 to fold the cover material 18 of a trim panel positioned in the die 10 into engagement with the side 26 of foundation board 22 to permit securing of the cover material 18 to the board 22 or may be moved to the position shown in FIGURE 4 so that covering and bonding material may be inserted into or removed from die 10 as will be seen in the consideration of the over-all operation of the die 10.

In over-all operation of the die 10, the sliding plates 66 are moved into the position illustrated in FIGURE 4 wherein the bonding and turning rules 30 and 32 are exposed. The die lid 14 is pivoted about hinge 34 into the open position wherein the surface of the resilient material 38 is exposed, and cover material 18 for a trim panel which is cut to the shape of the die so that it extends over the turning rules as shown in FIGURE 4 is positioned on the resilient material.

4
Bonding material, such as a pre-cut sheet of fiber bond, is then positioned on the covering material, also as shown in FIGURE 4. Alternatively adhesive may be applied directly to the cover material 18 or a foundation board 22 or the board may be impregnated with adhesive material, in which case the sheet type bonding material is not required.

A foundation board 22 is located on the open die lid 14 by means of the brackets 50 and recess 51 which are provided on die lid 14. The foundation board 22 is held in place on die lid 14 while the die lid 14 is closed.

Closing of the die lid 14 places the foundation board 22 in contact with the bonding material in a predetermined position with respect to the die base 12 and the cover material 18 thereon. On pressing downward on the die lid 14 in the closed position the resilient material 38 is compressed and the bonding and cover material are folded into engagement with the edge 24 of the foundation board 22 by turning rule 32 as shown in FIGURE 5.

The sliding plates 66 are then moved into the position shown in FIGURE 6 wherein they overlie the turning and bonding rules. As the sliding plates 66 are moved into the position shown in FIGURE 6 the bonding and cover material are folded into engagement with the surface 26 of foundation board 22 as shown.

The die 16 with the edge turned trim panel formed by the cover material 18 and foundation board 22 is then positioned in a press 80. An alternating signal is created by convenient means 82 between the platens 76 and 78 of the press. The alternating signal causes sealing of the cover material 18 to the foundation board 22 over the area engaged with the bonding rule 30 to complete a trim panel.

Should it be desired to emboss the trim panel it is only necessary to provide additional bonding rules 84 as alternatively shown in FIGURE 5 which bonding rules 84 are in the configuration of the embossing desired. The cover material 18 will then be sealed to the foundation board 22 to produce an embossed trim panel on producing an alternating signal between the sliding plates 66 and die lid 18 and the die base 12 when die 10 is placed in a press 80 as set forth above.

What we claim as our invention is:

1. A die for folding cover material around the edge of a foundation board to form a trim panel and for holding the cover material and foundation board in assembly while the cover material is electronically bonded to the foundation board, comprising a die base including a base plate of electrically conductive material and a bonding rule of electrically conductive material extending from said base plate, said bonding rule being formed to contact the periphery of a trim panel positioned within said die, said die base also including a turning rule of insulating material extending from said base plate adjacent said bonding rule, said turning rule being formed in the configuration of the edge of the foundation board around which the cover material is to be folded, and die lid means operably associated with said die base and insulated electrically therefrom for pressing the foundation board into engagement with the cover material, said turning rule operating with the edge of the foundation board during pressing of the foundation board into engagement with the cover material to fold the cover material into engagement with the edge of the foundation board, and guide block and sliding plate means electrically insulated from said die base also operably associated with said die base for folding the cover material into engagement with the surface of the foundation board remote from the die base and for holding the folded cover material during electronic sealing of the cover material to the foundation board.
2. Structure as claimed in claim 1 and further including a mounting block resiliently secured to said die base for movement perpendicular thereto and hinge means for securing the die lid means to said mounting block.

3. Structure as claimed in claim 1 wherein said sliding plate means is resiliently mounted in guide block means for movement perpendicular to said die base.

4. Structure as claimed in claim 1 and further including other bonding rules secured to said base plate operable to emboss a trim panel positioned within said die during sealing of the cover material.

5. A die for folding cover material around the edge of a foundation board to form a trim panel and for holding the cover material and foundation board in assembly while the cover material is electronically bonded to the foundation board, comprising a die base including a base plate of electrically conductive material and a bonding rule of electrically conductive material extending from said base plate, said bonding rule being formed to contact the periphery of a trim panel positioned within said die, said die base also including a turning rule of insulating material extending from said base plate adjacent said bonding rule, said turning rule being formed in the configuration of the edge of the foundation board around which the cover material is to be folded, said bonding rule being spaced inwardly from said turning rule with respect to a trim panel positioned in said die, and die lid means operably associated with said die base and insulated electrically therefrom for pressing the foundation board into engagement with the cover material, said turning rule cooperating with the edge of the foundation board during pressing of the foundation board into engagement with the cover material to fold the cover material into engagement with the edge of the foundation board, and guide block and sliding plate means electrically insulated from said die base also operably associated with said die base for folding the cover material into engagement with the surface of the foundation board remote from the die base and for holding the folded cover material during electronic sealing of the cover material to the foundation board.

6. A die for folding cover material around the edge of a foundation board to form a trim panel and for holding the cover material and foundation board in assembly while the cover material is electronically bonded to the foundation board, comprising a die base including a base plate of electrically conductive material and a bonding rule of electrically conductive material extending from said base plate, said bonding rule being formed to contact the periphery of a trim panel positioned within said die, said die base also including a turning rule of insulating material extending from said base plate adjacent said bonding rule, said turning rule being formed in the configuration of the edge of the foundation board around which the cover material is to be folded, said turning rule extending perpendicularly from the base plate a greater distance than said bonding rule, and die lid means operably associated with said die base and insulated electrically therefrom for pressing the foundation board into engagement with the cover material, said turning rule cooperating with the edge of the foundation board during pressing of the foundation board into engagement with the cover material to fold the cover material into engagement with the edge of the foundation board, and guide block and sliding plate means electrically insulated from said die base also operably associated with said die base for folding the cover material into engagement with the surface of the foundation board remote from the die base and for holding the folded cover material during electronic sealing of the cover material to the foundation board.

7. A die for folding cover material around the edge of a foundation board to form a trim panel and for holding the cover material and foundation board in assembly while the cover material is electronically bonded to the foundation board, comprising a die base including a base plate of electrically conductive material and a bonding rule of electrically conductive material extending perpendicularly from, secured to, and making electrical contact with said base plate, said bonding rule being formed to contact the periphery of a trim panel positioned within said die, said die base also including a turning rule of insulating material extending perpendicularly from said base plate adjacent said bonding rule, said turning rule being formed in the configuration of the edge of the foundation board around which the cover material is to be folded, said turning rule extending perpendicularly from the base plate a greater distance than said

tact the periphery of a trim panel positioned within said die, said die base also including a turning rule of insulating material extending perpendicularly from said base plate adjacent said bonding rule, said turning rule being formed in the configuration of the edge of the foundation board around which the cover material is to be folded, and resilient insulating supporting means within the area defined by the bonding rule for receiving the covering material thereon, die lid means operably associated with said die base and insulated electrically therefrom for pressing the foundation board in engagement with the cover material against the resilient supporting means to compress said resilient supporting means, said turning rule cooperating with the edge of the foundation board during compressing of the resilient supporting means to fold the cover material into engagement with the edge of the foundation board, and guide block and sliding plate means electrically insulated from said die base also operably associated with said die base for folding the cover material into engagement with the surface of the foundation board remote from the die base and for holding the folded cover material during electronic sealing of the cover material to the foundation board.

8. A die for folding cover material around the edge of a foundation board to form a trim panel and for holding the cover material and foundation board in assembly while the cover material is electronically bonded to the foundation board, comprising a die base including a base plate of electrically conductive material and a bonding rule of electrically conductive material extending perpendicularly from, secured to, and making electrical contact with said base plate, said bonding rule being formed to contact the periphery of a trim panel positioned within said die, said die base also including a turning rule of electrically insulating material extending perpendicularly from said base plate adjacent said bonding rule, said turning rule being formed in the configuration of the edge of the foundation board around which the cover material is to be folded, said bonding rule being spaced inwardly from said turning rule with respect to a trim panel positioned in said die, and resilient insulating supporting means within the area defined by the bonding rule for receiving the covering material thereon, die lid means operably associated with said die base and insulated electrically therefrom for pressing the foundation board against the resilient supporting means to compress said resilient supporting means, said turning rule cooperating with the edge of the foundation board during compressing of the resilient supporting means to fold the cover material into engagement with the edge of the foundation board, and guide block and sliding plate means electrically insulated from said die base also operably associated with said die base for folding the cover material into engagement with the surface of the foundation board remote from the die base and for holding the folded cover material during electronic sealing of the cover material to the foundation board.

9. A die for folding cover material around the edge of a foundation board to form a trim panel and for holding the cover material and foundation board in assembly while the cover material is electronically bonded to the foundation board, comprising a die base including a base plate of electrically conductive material and a bonding rule of electrically conductive material extending perpendicularly from, secured to, and making electrical contact with said base plate, said bonding rule being formed to contact the periphery of a trim panel positioned within said die, said die base also including a turning rule of insulating material extending perpendicularly from said base plate adjacent said bonding rule, said turning rule being formed in the configuration of the edge of the foundation board around which the cover material is to be folded, said turning rule extending perpendicularly from the base plate a greater distance than said

bonding rule, and resilient insulating supporting means within the area defined by the bonding rule for receiving the covering material thereon, die lid means operably associated with said die base and insulated electrically therefrom for pressing the foundation board in engagement with the cover material against the resilient supporting means to compress said resilient supporting means, said turning rule cooperating with the edge of the foundation board during compressing of the resilient supporting means to fold the cover material into engagement with the edge of the foundation board, and guide block and sliding plate means electrically insulated from said die base also operably associated with said die base for folding the cover material into engagement with the

5

surface of the foundation board remote from the die base and for holding the folded cover material during electronic sealing of the cover material to the foundation board.
